UNITED STATES PATENT OFFICE.

BARTHELEMY ALBERT FRANCOIS GUESNON DES MESNARDS, OF LATOUR PAR LAFORCE,
DORDOGNE, FRANCE.

HEATING APPARATUS.

1,187,979.

Specification of Letters Patent. Patented June 20, 1916.

Application filed May 7, 1913. Serial No. 766,189.

To all whom it may concern:

Be it known that I, BARTHELEMY ALBERT FRANCOIS GUESNON DES MESNARDS, citizen of the Republic of France, residing at Latour par Laforce, Dordogne, France, landlord, have invented certain new and useful Improvements in Heating Apparatus, of which the following is a specification, reference being had therein to the accompanying drawing.

The invention relates to improvements in heating apparatus and particularly that usually termed apparatus for central heating. It is intended to render the working of this apparatus more economical, more regular and safer.

It consists chiefly in a generator comprising a furnace combined with a boiler in such a manner that the steam produced in the latter, as well as the gases of combustion, are carried away simultaneously to the radiators or their equivalents. It is provided moreover with ejectors and injectors comprising a contrivance for cleaning, that is controlled automatically during the general working of the apparatus.

In the accompanying drawings which show by way of example a mode of execution of this invention, Figure 1 is a diagrammatic section of a generator for a heating apparatus of the kind referred to, Fig. 2 is an analogous section on a larger scale of the injector provided in said generator, and Fig. 3 shows a plan of a removable grate with which said generator may preferably be provided.

The generator shown in the drawings comprises: a hopper *a*, that may be used for storing fuel such as coal, coke or wood, and comprises at its lower portion a cylindrical part *a*¹; a frame *b* for holding the hopper *a*; an annular plate *c* mounted on said frame at a certain distance below the lower opening of the cylindrical part *a*¹ and having an inner diameter that is considerably larger than that of said cylindrical part *a*¹; a piece *d* that is generally conical and is provided with an outer rim *d*^o that rests on the annular plate *c*, and a series of internal parts *d*¹, parts *d*^o and *d*¹ having between them a number of pipes *e* arranged in a circle; an annular boiler *f* fitted in the central opening remaining between parts *d*¹ and preferably producing

instantaneous evaporation; a grate *g*, preferably of the oscillating type, arranged beneath the boiler *f*; a conical piping *h* fitted between the boiler *f* and the cylindrical part *a*¹ of the hopper *a*, and provided with a series of air inlets surrounded by a casing *h*¹ likewise provided with openings and serving as a damper when operated by means of a rod *h*²; a conical piece *i* that serves both as a chamber *j* for the gases of combustion (directed downward) and as an ash-pit; a supply pipe *k* that branches off from the receiving chamber *j*; and an ejector *l* placed at the opening of pipe *k* and connected with the boiler *f* in such a manner that it is fed during the general working so as to produce both an aspiration in chamber *j* and a forcing action in pipe *k*.

The boiler *f* is connected by a pipe *m* to a contrivance for supplying air under pressure consisting for instance of a receiver or tank *n* that is hermetically closed and combined with a small air compressor *o* that allows of placing the water stored in the receiver under pressure. A throttle device *p* such as a valve or the like is inserted in pipe *m*. The ejector *l* is moreover connected to a device for supplying compressed air according to requirements and consisting for instance of a pipe *q* placed parallel with pipe *m*, but branching off from the upper part of the receiver or tank instead of from the lower part of the same. The pipes *m* and *q* are both supplied with cocks *m*^o and *q*^o. Pipe *k* is connected up with the usual radiators, that are provided with a suitable exhaust pipe.

The mode of operation is as follows: The ejector *l* will influence the combustion, by drawing air by suction through the apertures of the part *h*. This air will support the combustion within this part. The suction will also take place within the conduits *e*, whereby air will be forced against the grate *g* and the fuel will be burned on the grate. The ejector will furthermore exert a suction effect at the foot of the discharge pipe *k* leading to the radiators (not shown) and this pipe therefore conveys not only the steam issuing from boiler *f* through the ejector, but also the combustion products from the combustion chamber.

In order to start the apparatus it is merely necessary to close the cock *m*^o, place some

glowing coal on the grate g , open the cock g^o and when the combustion has started reverse the position of said cocks, the grate being properly supplied with fuel, a large quantity of which can be stored in the hopper a so as to produce an automatic working for a considerable length of time.

The bore of the ejector l may, as shown in Fig. 2, comprise a cylindrical portion l^1 in which a piston l^2 is actuated, the rod of which passes through the opening of the bore without closing the same. The pressure of the fluid will act on the piston so as to regulate the supply of the fluid, and a suitable device can be supplied to produce a reverse action. This device may consist of a series of annular weights l^4 that slide freely in the cylinder l^1 and bear against stops l^5 , corresponding parts l^6 arranged at intervals on rod l^3 being made to successively abut against the weights, so as to obtain a continual cleaning of the bore. The part h is arranged on the other hand so as to be able to slide a little toward the top and receive a sort of fork r (Fig. 3) that forms an additional grate for holding back the fuel and allows of grate g being easily cleaned. Two cylindrical casings or tubes s , s^1 may moreover be arranged between the hopper a and plate c , that form an air-tight chamber, the first of these casings s being fast and connected up by a piping s^o with a chimney (not shown), through which the air is aspirated in case of a stop and through which the exhaust gases are allowed to escape in an opposite direction. The second casing or tube s^1 is movable and can slide upward in

order to give access to part h and the other devices.

The present invention can be applied to any kind of liquid or gaseous fuel by arranging the plant accordingly.

It is expressly to be understood that this mode of execution is only given by way of an example, the devices and arrangements may vary without departing from the principle of this invention.

The invention may also be applied for using the gases of combustion of any kind of furnace, such as a kitchen stove, the furnaces of works and the like.

Having now described the nature of my invention and the manner in which it is to be performed, what I claim is:

A heating plant, comprising in combination with a boiler and heating pipes a furnace for heating said boiler, an ejector communicating with the furnace and with the boiler and adapted to convey products of combustion together with steam from the boiler into the heating pipes, a reservoir containing water and air under pressure, and means for feeding said boiler from the water-space of said reservoir, or for connecting the same with the air-space above the water, substantially as described.

In testimony whereof I affix my signature in presence of two witnesses.

BARTHELEMY ALBERT FRANÇOIS
GUESNON, DES MESNARDS.

Witnesses:

HENRI ROSSARY,
HENRY PHILLIPS.
